Wesley G. Barr
ATTORNEY

UNITED STATES PATENT OFFICE.

CHARLES L. KNOTTS, OF SWISSVALE, PENNSYLVANIA, ASSIGNOR TO WESTINGHOUSE ELECTRIC & MANUFACTURING COMPANY, A CORPORATION OF PENNSYLVANIA.

TRANSFORMER TANK.

Application filed January 8, 1920. Serial No. 350,192.

To all whom it may concern:

Be it known that I, CHARLES L. KNOTTS, a citizen of the United States, and a resident of Swissvale, in the county of Allegheny and State of Pennsylvania, have invented a new and useful Improvement in Transformer Tanks, of which the following is a specification.

My invention relates to transformers and 10 to other electrical apparatus adapted to be normally immersed within a cooling fluid and it has particular relation to containers therefor.

One of the objects of my invention is to 15 provide a container for a high voltage transformer in which the terminal bushings are disposed in insulated compartments which are separate and independent of the main portion of the container whereby the 20 bushings may be individually removed for the purpose of inspection and repairs without the necessity of exposing the rest of the apparatus.

Another object of the invention is to provide 25 a container of the character described in which the terminal bushing may be so disposed as to decrease the overall height of the apparatus and at the same time to increase the safety factor thereof with respect to high voltage ruptures.

In the accompanying drawings;

Figure 1 is a plan view of a transformer embodying my invention, and

Fig. 2 is a vertical longitudinal sectional view 35 through the transformer casing taken on line II-II of Fig. 1, and illustrating the electrical apparatus in elevation.

Referring to the drawing, a transformer comprising a core member 1 embraced by 40 coils 2 and 3, is shown as positioned within a main containing tank or casing 4 provided with a removable cover 5. The casing 4 is filled with an insulating and cooling fluid which completely surrounds the transformer. A cooling coil 6 is mounted directly 45 above the transformer, in any preferred manner, and is also immersed within the cooling fluid.

The container 4 is provided with two oppositely disposed and outwardly extending compartments 7 which are shown as formed integral with the container and adjacent to the upper portion thereof. It will be observed that the portion of the side wall of 55 the tank 4 that is between the compart-

ments 7 and the interior of the container 4 constitutes partitions 8 which render the compartments entirely separate and independent of the container 4. The partitions 8 are preferably provided with apertures 60 9 adjacent to the lower portions thereof which establish communication between the compartments 7 and the interior of the container whereby the level of the insulating fluid will remain the same in both of the 65 compartments and the container.

The compartments 7 are each provided with a removable cover 10 through which extends a terminal bushing 11. The lower portion of the bushings 11 projects downwardly into the compartments 7 and the fluid contained therein to a point adjacent to the apertures 9. Conductors 12 carried by the bushings 11 extend through the apertures 9 and are connected to the main windings 75 of the transformer.

The interior of each of the compartments 7 is completely lined with insulating material which preferably comprises superposed layers of fuller board 13.

From the foregoing it will be apparent that by my construction the terminal bushings 11 may be disposed at the side of the transformer and in overlapped relation thereto rather than above the same, thereby materially decreasing the overall height of the apparatus while in no way reducing its insulating characteristics. Moreover by providing a separate compartment for each of the terminal bushings, which are independent from each other and from the main portion of the container, one of the bushings may be quickly and easily removed for the purpose of inspection and repairs without the necessity of disturbing or exposing the rest of the apparatus, as the fluid in the respective compartments completely seals the communicating apertures 9 and prevents dust or moisture from gaining access to the main portion of the container.

I claim as my invention:

1. A container for an oil-insulated electrical apparatus, lead-in bushings for said device, and auxiliary compartments for containing oil and adapted to contain said bushings positioned exterior to said main container but having communication therewith below the level of the insulating oil.
2. A container for an oil-insulated elec-

trical apparatus comprising a main body portion having a plurality of compartments containing oil on the side walls thereof and communicating with said body portion through apertures in said walls below the surface of the oil in the main body portion.

3. A container for a liquid-insulated electrical apparatus comprising a main body portion having a plurality of compartments formed integrally therewith and positioned exteriorly thereto, said compartments having communicating means with said body portion below the level of the insulating fluid whereby the same level of insulating fluid is maintained in the compartments and main portion of the container.

4. A container for an electrical apparatus, lead-in bushings, auxiliary chambers formed integrally with the main container and positioned exterior thereto, said bushings being positioned in said auxiliary chamber, communicating means between the container and auxiliary chambers whereby the same level of insulating fluid is maintained

in all of the apparatus containers, and an insulating lining for said auxiliary chambers.

5. The combination with a container having a plurality of communicating compartments for containing insulating liquid, of an electrical apparatus disposed within said container and terminal bushings extending downwardly into said compartments at each side of said container and spaced therefrom.

6. A container for an oil-insulated electrical apparatus comprising a main body portion, and a plurality of compartments for containing oil carried by said body portion, each of said compartments being separated from the interior of said body portion by partitions but in communication therewith through apertures in said partitions adjacent to the lower portion of said compartments.

In testimony whereof, I have hereunto subscribed my name this 15th day of December, 1919.

CHARLES L. KNOTTS.
